UNITED STATES PATENT OFFICE.

FREDERICK W. MARTIN, OF SPRINGFIELD, MASSACHUSETTS, ASSIGNOR TO HIMSELF AND HENRY W. HALLETT, OF SAME PLACE.

DESIGN FOR A FINGER OR OTHER RING.

Specification forming part of Design No. 5,970, dated July 2, 1872.

To all whom it may concern:

Be it known that I, FREDERICK W. MARTIN, of Springfield, in the county of Hampden and State of Massachusetts, have invented and produced a new and original Design for a Ring; and I do hereby declare that the following is a full, clear, and exact description thereof, reference being had to the accompanying drawing making a part of this specification, in which—

Figure 1 is a view, showing one-half the outer surface of the ring. Fig. 2 is a view, showing the other half of the outer surface; and Fig. 3 is an end view.

The nature of my invention is represented in the accompanying drawing, in which *a* is a finger-ring, the outer surface of which is of plain cylindrical form, and having upon said

outer surface a few bars of music engraved thereon. The staff and characters may be enameled in colors, and the general surface of the ring left the natural color of the metal; or the staff and characters may be left the natural color of the metal and the other surface enameled.

Having thus described my invention, what I claim as new, and desire to secure by Letters Patent, is—

1. A design for a ring having a music-staff engraved thereon, substantially as specified.
2. The design for a ring, substantially herein shown and described.

FREDERICK W. MARTIN.
